UNITED STATES PATENT OFFICE.

ANNETTE R. MOSES, OF NEW YORK, N. Y.

DESIGN FOR A CORSET-PROTECTING SHIELD.

No. 39,760.

Specification for Design.

Patented Jan. 12, 1909.

Application filed October 20, 1908. Serial No. 458,741. Term of patent 3½ years.

To all whom it may concern:

Be it known that I, ANNETTE R. MOSES, a citizen of the United States, residing at No. 123 East Twenty-sixth street, in the city, county, and State of New York, have invented a new, original, and ornamental Design in Corset-Protecting Shields, of which the following is a specification, reference being had to the accompanying drawing, forming part thereof.

The figure is a view of "corset protecting shields" showing my new design.

I claim—

The ornamental design for "a corset protecting shield" as shown.

ANNETTE R. MOSES.
